(57) **CLAIM**

The ornamental design for a hunting scent generator, as shown and described.

DESCRIPTION

FIG. 1 is a right front perspective view of a hunting scent generator showing my new design.

FIG. 2 is a left rear perspective view thereof.

FIG. 3 is a front elevation view thereof.

FIG. 4 is a right side elevation view thereof.

FIG. 5 is a rear elevation view thereof.

FIG. 6 is a left side elevation view thereof.

FIG. 7 is a top plan view thereof; and,

FIG. 8 is a bottom plan view thereof.

The features of the hunting scent generator depicted in dashed lines form no part of the claimed design.

1 Claim, 7 Drawing Sheets
